United States Patent

Des. 238,624

Patented Feb. 3, 1976

238,624

BOBBIN CASE

Margaret A. McArthur, 4289 Lake Road,
Youngstown, Ohio 44514

Filed Mar. 29, 1974, Ser. No. 456,214

Term of patent 14 years

Int. Cl. D3—99

U.S. Cl. D3—19 B

FIG. 1

FIG. 2

FIG. 3

FIG. 1 is a top perspective view of a bobbin case showing my new design;

FIG. 2 is a top plan view thereof with the rotatable cover removed; and

FIG. 3 is a side elevational view, the bottom being substantially plain.

I claim:

The ornamental design for a bobbin case, as shown and described.
